(57) **CLAIM**

The ornamental design for a packaging container, as shown and described.

DESCRIPTION

FIG. 1 is a front view of a packaging container showing our new design;

FIG. 2 is a rear view thereof;

FIG. 3 is a right side view thereof; the left side view is a mirror image of the right side view;

FIG. 4 is a top plan view thereof;

FIG. 5 is a bottom plan view thereof;

FIG. 6 is an enlarged view thereof taken along the line 6-6 in FIG. 1;

FIG. 7 is a cross-sectional view thereof taken along the line 7-7 in FIG. 4;

FIG. 8 is a cross-sectional view thereof taken along the line 8-8 in FIG. 6; and,

FIG. 9 is a perspective view thereof showing the state in use. The broken lines depict portions of the packaging container that form no part of the claimed design, and the dash-dot-dash lines illustrate the boundary of the claimed design that form no part thereof.
